US0D1114255S

(12) **United States Design Patent** (10) Patent No.: **US D1,114,255 S**
(45) Date of Patent: ** Feb. 17, 2026

(54) **LIP IMPLANT**

(71) Applicant: **SurgiSil, L.L.P.**, Plano, TX (US)

(72) Inventors: **Peter Raphael**, Plano, TX (US); **Scott Harris**, Dallas, TX (US)

(73) Assignee: **SURGISIL, L.L.P.**, Plano, TX (US)

(**) Term: **15 Years**

(21) Appl. No.: **29/738,540**

(22) Filed: **Jun. 18, 2020**
